Primary Examiner — Clint A Samuel*(74) Attorney, Agent, or Firm* — iPA & iPM(57) **CLAIM**

The ornamental design for a LED light bulb string, as shown and described.

DESCRIPTION

FIG. 1 is a first perspective view from above of a LED light bulb string showing my new design, with area 9 further enlarged for illustrating details in FIG. 9;

FIG. 2 is a perspective view from below thereof, with area 10 further enlarged for illustrating details in FIG. 10;

FIG. 3 is a top view thereof;

FIG. 4 is a bottom view thereof;

FIG. 5 is left side view thereof, with area 11 further enlarged for illustrating details in FIG. 11;

FIG. 6 is a right side view thereof, with area 12 further enlarged for illustrating details in FIG. 12;

FIG. 7 is a back view thereof;

FIG. 8 is a front view thereof;

FIG. 9 is an enlarged detailed perspective view of area 9 in FIG. 1;

FIG. 10 is an enlarged detailed perspective view of area 10 in FIG. 2;

FIG. 11 is an enlarged detailed left side view of area 11 in FIG. 5; and,

FIG. 12 is an enlarged detailed right side view of area 12 in FIG. 6.

Broken lines showing in the drawings are for purpose of illustrating environment structure and form no part of the claimed design.

The LED light bulb string is shown with a symbolic break in its length. The appearance of any portion of the article between the break lines forms no part of the claimed design.
